UNITED STATES PATENT OFFICE.

EUGENE HOLT AND LAFAYETTE HOLT, OF BURLINGTON, NORTH CAROLINA.

LEAD-LINED YARN-BEAM.

1,207,043.

Specification of Letters Patent. Patented Dec. 5, 1916.

Application filed September 10, 1914. Serial No. 861,078.

To all whom it may concern:

Be it known that we, EUGENE HOLT and LAFAYETTE HOLT, citizens of the United States, residing at Burlington, in the county 5 of Alamance and State of North Carolina, have invented certain new and useful Improvements in Lead-Lined Yarn-Beams, of which the following is a specification.

In connection with yarn beams which are 10 used for holding the yarn during the dyeing, cleaning and other operations, during which the material and of necessity the beam or holding means are subjected to the action of acids and other chemicals, it has been found 15 expedient for purposes of economy to employ base metals and similar materials which can be molded or cast in the desired form at comparatively small expense, but such materials are objectionable from the fact that 20 being exposed to the chemicals necessary to the proper treatment of the yarn, the beam, and more especially that portion of the beam with which the yarn contacts, becomes corroded, and this corrosion or stain incident 25 thereto communicates itself to the yarn and renders the latter commercially inferior or unfit for use, thereby involving a certain percentage of loss in the product.

The object of the present invention is to 30 avoid these disadvantages and prevent deterioration of the product or any part of it, while providing for a construction of yarn beam which shall be of a cost which is little, if any, in excess of those produced under the 35 methods heretofore practised, and wherein the means provided for the protection of the yarn or contents of the beam shall be of such a character as to permit of the comparatively rough or coarse formation of the body 40 portion of the beam wherein the strength of the structure resides.

With this object in view, the invention consists in a certain construction and arrangement of parts hereinafter fully explained, it being understood that changes in 45 the form, proportions and details of the construction may be resorted to within the scope of the claims, without departing from the spirit of the invention or sacrificing any 50 of the advantages thereof.

In the accompanying drawing, Figure 1 is 55 a vertical sectional view of a yarn beam arranged in its normal or operative position within a vat or retort which may be employed in the various dyeing and other operations to which the yarn is subjected, said

vat or retort being indicated by dotted lines; Fig. 2 is an end view of the beam on the line 2-2 of Fig. 1; Fig. 3 is a transverse sectional view showing the inner surface of one 60 of the heads on the plane indicated by the line 3-3 of Fig. 1; Fig. 4 is a detail enlarged fragmental section of the beam barrel.

The hoop-shaped body portion of the yarn beam may be cast or the barrel portion 10 65 thereof may be drawn, rolled or otherwise constructed with the heads 11 cast or stamped and suitably fitted and secured thereto, said heads in the construction illustrated consisting of a hub 12, ring or rim 13 and spokes 70 14, the ends of the barrel being fitted with plugs 15 and 16 of which the latter, when used as contemplated (namely for the introduction or removal of the dye liquors through one end of the barrel), should be 75 perforated, as indicated at 17. The barrel also is perforated more or less uniformly, or to a greater or less extent as may be found expedient in practice to permit of the passage of the dye and other liquors 80 through either outwardly or inwardly, as may be preferred, to insure the proper distribution of said liquors throughout the body of the yarn which is wound or otherwise placed upon the exterior of the barrel 85 between the planes of the heads, and is thereby held during the treatment to which the yarn is subjected.

Regarding the exterior surface of the barrel and the inner or facing surfaces of 90 the heads as the bearing surfaces or yarn-holding surfaces of the beam, this invention contemplates providing said surfaces with a coating or sheath of a material which is non-corrosive or is not affected by the chemicals and other materials to which the yarn 95 is subjected in treatment, such a sheath being indicated in the drawing at 18 and the same being extended outward at the inner surfaces of the heads to form disk-like plates 100 19. It has been found, again as a matter of economy, that this sheath may be made of lead or a composition thereof, applied either as a coating or as a sheet to the indicated surfaces of the body or main structure of the beam, and it is only with this sheath that the 105 yarn comes in contact during the described operations. As the corrosion to which the metal forming the body of the beam is subjected is not communicated to the yarn except when the latter comes into actual contact therewith, a sheath arranged as de- 110

scribed forms a complete protection, and obviously the natural qualities of lead render it readily workable in providing a perfectly smooth surface finish, which still further adds to the efficiency of the beam for the intended purposes. Thus while the qualities of lead and similar non-corrosive materials are inappropriate and impracticable as materials for forming the body portion of the beam, owing to the comparatively rough usage and strains to which such structures are subjected, they are not only suitable but peculiarly adapted to the purpose herein described when employed as a sheath to form the yarn-bearing surfaces of the beam, and while adding to the efficiency of the beam in preventing injury to or deterioration of the yarn, add substantially to the durability and period of usefulness of the device.

20 What is claimed as new is:

1. A yarn beam having a body portion of base metal and provided with a yarn-bearing surface of non-corrosive metal.
2. A yarn beam having a body portion of base metal and provided with a sheath of non-corrosive metal forming a yarn-bearing surface.
3. A yarn beam having a body portion of base metal provided with a yarn-bearing surface of lead.
4. A yarn beam having a hollow barrel

and terminal heads provided on their yarn-bearing surfaces with a sheath of substantially impervious non-corrosive material.

5. A yarn beam having a perforated barrel closed at one end and having an inlet at the other end and fitted with terminal heads, and a sheath of non-corrosive metal arranged upon the exterior surface of the barrel and the facing surfaces of the heads, the barrel covering portion thereof being perforated in registration with the perforations of the barrel.

6. A yarn beam provided with a yarn bearing surface of non-corrosive metal.

7. A yarn beam provided with a yarn bearing surface of non-corrosive metal and including a perforate barrel.

8. A yarn beam provided with a yarn bearing surface of substantially impervious non-corrosive material.

9. A yarn beam having a perforate barrel, and a substantially impervious non-corrosive sheath provided on the yarn bearing surface of the beam.

In testimony whereof we affix our signatures in presence of two witnesses.
